UNITED STATES PATENT OFFICE.

ROBERT SCHEANBLUM AND GRACE SCHEANBLUM, OF DANBURY, CONNECTICUT.

COMBINATION HAIR FORM AND TIE.

1,413,360.

Specification of Letters Patent.

Patented Apr. 18, 1922.

Application filed February 17, 1921. Serial No. 445,809.

To all whom it may concern:

Be it known that we, ROBERT SCHEANBLUM and GRACE SCHEANBLUM, citizens of the United States, residing at Danbury, in the 5 county of Fairfield and State of Connecticut, have invented a certain new and useful Combination Hair Form and Tie, of which the following is a specification.

This invention is a combination hair form 10 and tie intended for use in the arranging of ladies' hair in an attractive and pleasing manner and relates more especially to a device for facilitating the making of psyches, swirls, rolls, puffs and similar conformations.

Hair supports and foundations to facilitate the fixing of hair in desired conformations have been heretofore employed, and the object of the present invention is to simplify 20 the construction of such devices, economize in their manufacture, facilitate their application and enable the hair to be more readily and easily manipulated and dressed.

In its preferred practical form, the invention embodies an open base loop adapted to seat upon the head and with which is associated means for detachably maintaining the loop in closed position, in combination with a plurality of distending wires, which 30 extend diametrically across the loop in angular relation to one another and which are longitudinally arched to form a foundation or frame through which the hair may be passed and on which it may be built up or 35 formed into the desired conformations.

In practice, the attaching means of the loop may be disengaged to permit of the opening of the loop so that the device may be passed about the hair without requiring 40 the threading of the hair through the loop, although the construction is such that the hair may be divided into a plurality of strands, some of which may be threaded through the loop and one of which may be 45 passed into the loop without requiring the threading operation. When the loop is closed with the hair extending therethrough, a convenient and light foundation is formed which greatly facilitates the production of 50 the hair conformations desired.

Features of the invention, other than those adverted to, will be apparent from the hereinafter detailed description and claims, when read in conjunction with the accompanying drawings.

The accompanying drawings illustrate different practical embodiments of the invention, but the constructions herein shown are to be understood as illustrative, only, and not as defining the limits of the invention. 60

Figure 1 is a view of the back of a head showing the manner in which the invention may be applied to the head.

Figure 2 is a perspective view of the preferred form of the invention; and,

Figure 3 is a like view of a modified form of construction.

The device of the present invention, as shown in Figure 2, is formed of resilient or 70 spring wire, which, in practice, is preferably covered with cotton, silk, hair or any other desired material, so as to enclose and conceal the wire. In manufacturing the construction, one end of the wire is first 75 formed into a hook 1 and a portion of the length of the wire is then bent to form a loop 2. The wire changes direction at 3, extends diametrically across the loop in arched condition, and its free end is coiled 80 about the loop 2 at 4. This diametrically extending wire is designated by the reference numeral 5.

One end of a second wire 6 is next coiled 85 about the loop 2, as at 7, is arched longitudinally and coiled at its center at 8 about the wire 5 and from thence extends to the opposite side of the loop 2 where it is secured to the loop by a coil 9 as shown.

A hair form thus constructed embodies a 90 base loop 2 and diametrically extending, arched distending wires 5 and 6, which divide the frame into four sections or openings. In dressing the hair, the frame may be employed in different ways. For example, if so desired, the hook 1 may be operated to open the base loop 2, whereupon it will take the position shown in dotted lines in Figure 2, thereby opening one fourth of the loop. The frame may then be passed 100 over a strand of hair without necessitating the threading of the hair through the loop, whereupon the hook 1 is hooked over the wire 5, as shown in full lines in Figure 2 to enclose the strand of hair. As the hair will 105 not be clamped within the loop by the fastening of the hook, the device may now be properly and comfortably adjusted on the head and the hair thereafter curled or worked about the device, so as to build up 110

the conformation desired and completely cover the frame being finally secured in position by hair pins in the usual manner.

Another manner of employing the frame is to divide the hair into a plurality of strands and thread the strands through different sections of the frame or to thread the strands through certain sections of the frame after one strand has been encompassed by the frame while the hook is detached. The manner of manipulating the frame is, however, optional with the hair dresser and the two examples given are merely illustrative. In any event, there is no clamping of the hair in position and the device may be at all times properly adjusted without injury to the hair so as to partake of the most comfortable and aesthetic position.

In Figure 3 of the drawings, a modified form of invention is illustrated and in constructing this form, the base loop 10 is made closed by coiling one end of the wire as at 12 about an intermediate portion of the wire. The wire changes direction adjacent the coil 12 and extends diametrically of the loop 10, arched longitudinally, and is provided at its free end with a hook 13 adapted to detachably engage with the opposite side of the loop as clearly shown in full lines in Figure 3. This diametrically extending wire is designated by the reference numeral 14. One end of a second distending wire 15 is coiled about the loop 2 at 16, is passed diametrically of the loop, coiled intermediate its ends at 17 about the wire 14, and coiled at its opposite end at 18 around the opposite side of the loop. This manner of making the frame divides the wire 14, into two parts, one part 19 of which may be termed a tongue 40 and the free end of which tongue carries the hook 13. In utilizing the modified form of frame, as shown in Figure 3, the hair may be divided into four strands and passed through the different sections of the frame, or, if desired, the hook may be disengaged from the loop 2 to partake of the dotted line position, whereupon the hair may be threaded through the loop and divided on either side of the tongue 19 in a more expeditious 50 and easy manner than it can be threaded in single strands through each section adjacent the tongue. However, in this as well as in the preferred form of the invention, the manner of employing the frame is optional 55 with the hair dresser.

Both forms of the invention are simple in construction, may be economically manufactured and are efficient in use. They provide

a convenient and ready device for fashioning the hair as may be desired and permit of a large variety of hair conformations. They are equally adapted for the formation of psyches, swirls, or other conformations normally formed on the top or back of the head, and dips, puffs or other conformations which are usually formed on the sides of the head.

Having thus fully described the invention, what we claim as new and desire to secure by Letters Patent is:

1. A combination hair form and tie embodying a base loop formed from wire and adapted to be seated on the head, and a plurality of distending wires arched longitudinally and extending diametrically of the base loop in angular relation to one another, said base loop being an open loop having one free end shaped into the form of a hook adapted to hook over one of the distending wires to maintain the base loop in normally closed condition, but which hook may be released to permit the loop to be opened so that it may be passed about a strand of hair.

2. A combination hair form and tie embodying a wire bent for a portion of its length to form an open loop the free end of which loop is provided with a hook, and the remainder of the wire being bent to extend transversely across the loop to the opposite side thereof and there permanently secured to the loop to constitute a distending element which is arched longitudinally, and a second wire extending transversely of the loop, in angular relation to said distending element, and permanently secured at its opposite ends to the loop and intermediate its ends to said distending element.

3. A combination hair form and tie embodying a wire bent to form a base loop and also an arched distending element extending transversely of the base loop one end of the wire being free from permanent attachment to the remainder of the wire, except in so far as said end is integral with the wire, attaching means associated with said free end of the wire for detachably securing said free end to an intermediate portion of wire, and a second wire extending transversely of the loop in angular relation to the said distending element and permanently secured at its opposite ends to the loop and intermediate its ends to said distending element.

In testimony whereof, we have signed our names to this specification.

ROBERT SCHEANBLUM.
GRACE SCHEANBLUM.
